UNITED STATES PATENT OFFICE

168,806

LAPEL ORNAMENT OR THE LIKE

Ruth E. Rearick, Miami, Fla.

Application March 9, 1951, Serial No. 14,437

Term of patent 7 years

(Cl. D45—19)

To all whom it may concern:

Ruth E. Rearick, a citizen of the United States, and a resident of Miami, in the county of Dade and State of Florida, has invented a new, original, and ornamental Design for a Lapel Ornament or the like, of which the following is a specification.

Reference being to the accompanying drawings, forming part thereof, in which:

I claim:

The ornamental design for a lapel ornament or the like, as shown.

RUTH E. REARICK.
